(No Model.).

J. GRUNDLER.
FIFTH WHEEL.

No. 581,858.

Patented May 4, 1897.

UNITED STATES PATENT OFFICE.

JOSEPH GRUNDLER, OF NEW YORK, N. Y.

FIFTH-WHEEL.

SPECIFICATION forming part of Letters Patent No. 581,858, dated May 4, 1897.

Application filed December 7, 1896. Serial No. 614,692. (No model.)

To all whom it may concern:

Be it known that I, JOSEPH GRUNDLER, a citizen of the United States, and a resident of New York city, county of New York, and 5 State of New York, have invented certain new and useful Improvements in Fifth-Wheels, of which the following is a specification, reference being had to the accompanying drawings, forming a part thereof, in which similar 10 letters of reference indicate corresponding parts.

This invention relates to certain improvements in fifth-wheels for vehicles, which has for its object to furnish a device which shall 15 obviate the friction of and reduce wear of the wear-plates of the wheel as now constructed, and to produce a device that will operate easily and economize the use of lubricating material therefor.

20 The invention will be hereinafter fully described, and specifically set forth in the annexed claim.

In the accompanying drawings, forming 25 part of this specification, Figure 1 is a front elevation of my invention, showing the same in position for use. Fig. 2 is a sectional view of the device, showing the manner of attachment of plates and rollers. Fig. 3 is a top view of the casing and rollers and plates in 30 dotted lines, and Fig. 4 is a detail section of the plates and casing.

In carrying out my invention I employ two circular bearing or wear plates A and A', which are secured to the upper bolster B and lower bolster B' of the front part of a wagon, 35 respectively, by bolts b and b', which are countersunk in said plates, as shown at b², the bolsters being connected by the usual king-bolt. The said plates A and A' are 40 formed with annular flanges a and a' upon their upper and lower edges. An annular frame or casing C, consisting of the two parallel annular sections C' and C², secured to each other by bolts c, is interposed between 45 the said plates, said case having a plurality of antifriction-rollers c', transversely pivoted therein by pivots c², the flanges a and a' of the plates resting upon the respective upper and lower edges a² and a³ of said casing, per-

mitting the plates A and A' to contact with 50 the rollers c' and rotate thereon.

The rollers c' are tapered longitudinally, as shown in the drawings, the thicker portions being pivoted in the outer plate C, and the plates A and A' are made thinner at the 55 outer portions, whereby when they are rotated all the parts thereof will bear upon the rollers and all parts of the device will operate easily.

The operation of the device is as follows: 60 The two bearing-plates A and A' of the bolsters B and B' having been secured in their respective positions upon the roller-casing C and the bolsters having been attached in the usual manner, it will be seen that when the 65 bolster B' of the front axle is turned in either direction the bearing-plates A and A' will bear directly upon the rollers c' and not upon each other, and thus avoid the heavy friction and wear and tear and expensive use of lubricants consequent upon the old way of 70 constructing fifth-wheels.

Having thus described my invention, what I claim as new, and desire to secure by Letters Patent, is—

75 A fifth-wheel for vehicles, comprising the upper and lower annular bearing-plates, said plates having flanges on their outer edges and their inner surfaces beveled from the inner edges outwardly, the casing having tapered antifriction-rollers pivoted therein extending the width thereof, said casing adapted to receive the flanges of said plates upon its edges, the smaller ends of said rollers pivoted in the inner plates of the casing, whereby the 80 beveled plates bear upon the entire faces of the rollers at all times, and means for securing the plates to the bolsters, substantially as shown and described.

In testimony that I claim the foregoing as 90 my invention I have signed my name, in presence of two witnesses, this 25th day of November, 1896.

JOSEPH GRUNDLER.

Witnesses:

C. SEDGWICK,
B. MCCOMB.
